UNITED STATES PATENT OFFICE.

PAUL R. ZYLKA, OF KALISPELL, MONTANA.

DESIGN FOR A COMBINATION-TOOL.

57,097.

Specification for Design.

Patented Feb. 8, 1921.

Application filed May 24, 1920. Serial No. 383,992. Term of patent 14 years.

To all whom it may concern:

Be it known that I, PAUL R. ZYLKA, a citizen of the United States, residing at Kalispell, in the county of Flathead and State of Montana, have invented a new, original, and ornamental Design for Combination-Tools, of which the following is a specification, reference being had to the accompanying drawing, forming part thereof.

Figure 1 is a side elevation.

Fig. 2 is an edge view.

Fig. 3 is an end view.

I claim:

The ornamental design for a combination tool as shown.

PAUL R. ZYLKA.
